Dudley & Darby

UNITED STATES PATENT OFFICE

DUDLEY D. LEVY, OF NEW YORK, N. Y., ASSIGNOR TO DUDLEY RESEARCH CORPORATION, OF NEW YORK, N. Y., A CORPORATION OF NEW YORK

DENTAL TOOL

Application filed July 7, 1928. Serial No. 290,920.

This invention relates to a tool which is designed for use in dental surgery or in bone surgery, and has for its object the provision of a simple and efficient tool for converting rotary, or shaft motion, into longitudinally reciprocal motion for tamping, chiseling and for other purposes.

Another object includes the provision of a dental tool having a reciprocating member or hammer and means for reciprocating said hammer to thereby impart a succession of rapid hammer blows to a tool or tool holding head.

A further object is the provision of means whereby the hammer is brought into action only by pressure on the tool.

Other objects will appear hereinafter and I obtain these objects by the construction illustrated in the accompanying drawings in which—

Figure 1 is a view showing my device attached to a drive pulley and holder;

Fig. 2 is a view partly in section taken on the line 2—2 of Fig. 1;

Fig. 3 is a view similar to Fig. 2, but showing the hammer tensioned and ready to descend upon the tool head; and

Fig. 4 is a detailed view of the pawl and tripping mechanism.

Like numerals refer to similar parts throughout the several views.

In a preferred form of construction I provide a shell or casing 10, of suitable dimensions, wherein is contained my improved and new assembly. The tool carrying end of said shell engages a threaded hollow member 11 within which is reciprocally held the tool holding member 12 by a pin 13; or its equivalent, extending into slot 14 in the neck 15 of

said tool holding member. Neck 15 is threaded internally and is designed to receive a tool 16, which may be a chisel, or other tool suited for the work at hand.

The tool holding member 12 has an enlarged head to receive the hammer blows of the hammer 17 as it reciprocates on the angular drive shaft 18 in the manner about to be described. Shaft 18 has a round tip 20 to rotatively and reciprocally fit into the plain bore of the tool holding member 12. This

member is held against rotation by pin 13 engaging slot 14. The upper end 23 of drive shaft 18 is provided with a washer 24 welded or otherwise fastened on the shaft and against which abuts spring 25 on the one side and the assembling nut 26 on the other. The drive end 23 of shaft 18 may be tapered and is designed to receive the engaging member (not shown) of the driven shaft 27 which carries pulley 28 or its equivalent. The driven shaft and the engaging member are carried in a suitable housing 29 of known construction and the end of the housing frictionally fits on the extension of nut 26.

It will be noted that hammer 17 is provided with a cavity to receive a portion of spring 25. Said hammer is also provided exteriorly with a rather coarse screw thread 30, which begins with a shallow portion 31 and ends in a blind thread and smooth head 32. A pawl 33 having a downwardly curved tail 34 is pivotally mounted in exterior lugs 35. A spring 36 depresses the tail 34 to engage the screw thread 30 under conditions stated below.

The head end 37 of pawl 33 is beveled and normally engages the seat 38 of the pawl controlling slide head 40 of slide member 41. This member is slidably held by cleat 42 on which is located the spring anchoring pin 43. A pin 45 is fastened in slide member 41 and serves for holding the other end of the slide tensioning spring 44. The pin itself is mounted to move longitudinally in the shell slot 46 and spring 44 tensions pin 45 and its slide towards the pawl 33. From this construction it is apparent that the tension of spring 44 lifts pawl 33 out of engagement with threads 30 by a wedging action.

In Fig. 2 pawl 33 is shown in engaging or locked position, that is the tail 34 is in engagement with the screw thread 30 of hammer 17 and the head end 37 engages seat 38 of the slide member 41. By reason of the rotation of the hammer, as shown by the arrow, said hammer is tensioned against spring 25 into the position shown in Fig. 3. The instant that tail 34 reaches the blind thread 50 on head 32 it is tripped to disengage the mouth 38 of slide 41 which is then moved

into open position by spring 44. Because tail 34 is lifted above threads 30 the hammer is released to strike the head of the tool holding member 12, thereby imparting a sharp blow to said member and its tool, the force of which is dependent on the intensity of spring 25. The spring is removable and a spring of different intensity may be used suited for the work that is to be done.

10 As the hammer strikes member 12 and moves it a short distance outwards, said member also strikes the trip lug 21 and thereby moves the lug and its pin, together with slide 41, to the closed position shown in Fig. 2. The tail 34 of trip 33 is then again depressed, but since the hammer is moved forward the tail lies outside of the thread end 31. When in this position the hammer will rotate idly without being wound up. The moment, however, that pressure is applied to the tool and the tool holding head is pressed inward against the hammer so as to move it also a short distance inwards, tail 34 will engage threads 30 to repeat the action just described.

15 It is obvious that the number of hammer blows per unit of time is dependent upon the revolutions of the hammer and its drive unit. In the construction from which the illustrative drawings herein are made, I obtained 120 hammer blows per minute at 3000 R. P. M. for its most efficient operation. The speed, however, may be varied within wide ranges.

20 35 Having now described my invention, what I claim as new and useful and desire to secure by Letters Patent is:—

1. In a device of the class described, the combination with a casing, of a tool holding member mounted in said casing, said member having a head, a drive shaft rotatively mounted in said casing and extending substantially the length thereof, said shaft in free engagement with the head of said tool holding member, a hammer member mounted to reciprocate on said shaft, a spring on said shaft for forcing said hammer member into contact with the head of said tool holding member, means including a pivotally supported pawl for engaging said hammer member to force it against said spring, and means for temporarily releasing said hammer engaging means to thereby impart a rapid succession of blows on the head of the tool holding member.

2. In a dental tool, a hammer rotatively mounted and having screw threads thereon and tensioning means therein, means for engaging said threads, means for rotating said hammer to thereby move said rotating hammer longitudinally against said tensioning means, means for releasing said thread engaging means, and means to again cause said thread engaging means to become effective.

3. In a dental tool, a hammer rotatively

25 mounted and having screw threads thereon and a cavity therein, a spring carried in said cavity and extending therefrom, a pawl for engaging said screw threads, a drive shaft on which the hammer is adapted to move against said spring as it is rotated, means for holding said pawl in engagement with the screw threads, and means for temporarily holding said pawl in disengaged position.

4. In a dental tool, a hammer having screw threads thereon, and said threads terminating blindly in the hammer head, a pawl mounted to engage said threads to move the hammer longitudinally as it is rotated against tensioning means, said pawl being lifted out of the thread engaging position by the blind thread, a slidable catch member tensioned to engage the pawl to hold said pawl in lifted position to permit the hammer to be moved by the energy of said tensioning means whereby said pawl holding means is moved to release said pawl for reengagement with the screw thread.

5. In a device of the class described, the combination with a casing, of a tool holding member mounted in said casing, means for holding said tool holding member against rotation, an angular drive shaft mounted to rotate in said casing, said shaft having a round tip to engage said tool holding member, a hammer mounted on said drive shaft to rotate therewith, means for reciprocating said hammer member on said shaft to impart hammer blows on said tool holding member, and means to render said reciprocating means effective by applying pressure to the tool holding member.

10 In testimony whereof I have hereunto set my hand on this 3rd day of July, A. D. 1928.

DUDLEY D. LEVY.
